UNITED STATES PATENT OFFICE.

CHARLES H. DENISON, OF NEW YORK, N. Y.

IMPROVEMENT IN PAPER-COLLAR MACHINES.

Specification forming part of Letters Patent No. 122,444, dated January 2, 1872.

To all whom it may concern:

Be it known that I, CHARLES H. DENISON, of the city, county, and State of New York, have invented a new and useful Improved Paper-Collar Machine; and I do hereby declare that the following is a full, clear, and exact description thereof, reference being had to the accompanying drawing making a part of this specification, and to the letters of reference marked thereon, in which—

Figure 1 is a plan view of my invention. Fig. 2 is a front view of the same. Fig. 3 is a plan view of the embossing-plate with the embosser attached thereto. Fig. 4 is an end view of the same. Fig. 5 is a plan view of the lower plate with the folding-knife and counter for the embossing-tool attached. Fig. 6 is a transverse section of the same through line Y of Fig. 5. Fig. 7 is a rear view of the embossing and folding plunger, showing the arrangement of the gauges. Fig. 8 is a vertical section of the punching apparatus through line O'' of Fig. 1. Fig. 9 is a side view of a portion of the feeding-chain. Fig. 10 is a plan view of the same. Fig. 11 is a rear view of the punching apparatus; and Fig. 12 is a vertical section through the punch-plunger at line U.

My invention relates to a machine for manufacturing paper collars, or collars composed of paper and cloth combined; and it consists in the construction and arrangement of the same, in which a folding-knife is located beneath the embossing-plunger and upon the bed of the machine, the knife being attached to a movable piece which is slotted to receive set-screws, so that the piece with the knife may be adjustable to any desired position. The knife-counter is a separate piece, and is placed in a recess made in the embossing-plate to receive it, so that the counter may be quickly and easily changed to conform to any particular form of knife which may be being used. The feed-chain is made in small pieces hinged together, and has at certain intervals pieces attached thereto, having a slot made through each, into which is fitted to slide freely a tongue, to one end of which is attached one end of an elastic spring or rubber, the other end of said rubber being attached to the flat part of the chain. The feed-chain is carried over two rollers, one of them (the feed-roller) being actuated by a toothed segment and rod attached to a wheel on the main shaft of the machine,

and a recess is made in the table or platform, so that one of the feed-chains may be moved laterally upon the feed-rollers, so as to bring the chains nearer together or further apart, according to the length of the blank collars being passed through the machine. Arranged upon the same frame, and to the rear of the embossing and folding apparatus, is a punching apparatus, consisting of three punches with their dies, the two end punches being arranged upon a plunger in ways or guides, so that they may be moved longitudinally along the plunger; and these two end punches move vertically in guides having the dies made thereon, said dies or their plates resting upon the bed of the machine, and secured thereto by set-screws passing up through the bed of the machine into the die-plates; and arranged in this way the two end punches and dies may, by loosening the set-screw of each, be moved either nearer together or further apart to suit the length of collar being operated upon. The middle punch passes up through a transverse slot in the plunger, and is secured thereto in such manner that, by loosening a nut upon its upper end, it may be moved a little either way transversely with reference to the plunger, and the die is arranged upon the bed so that by loosening the set-screw beneath it may be moved to correspond with the position of its punch. A roller or shaft, e², is placed at the end of the machine, upon which the feed-chains e¹ are carried, which carry the collar from the embossing and folding apparatus to the punchers, said chains being also placed upon and actuated by the same feed-roller that actuates the other chains that carry the collars to the embosser and folder.

That others skilled in the art may be able to make and use my invention, I will proceed to describe the same both in construction and operation.

In the drawing, B represents a frame having the uprights A and a bed, L', between. A shaft, E', has its bearings in these uprights at A³, and upon this shaft are arranged the eccentrics carrying the rods H'', attached at their lower ends to the plunger G, which has guides h³ operating in the guide-ways h². In the lower side of the plunger are made dovetailed recesses a transversely across the plunger, and a plate, G', having corresponding dovetailed projec-

tions a^2 thereon, is attached to the lower side of the plunger by inserting the said projections in the dovetailed recesses a . To this plate is attached the embossing-plate G'' having the die f^2 attached around the edge, and a longitudinal recess or trough is made in the embossing-plate, into which is inserted the piece f having the curved channel f^1 made therein, which forms a counter-die for the folding-knife, which will be hereinafter explained. L represents a plate having a recess, l^1 , at each end, along which pass the feeding-chains, and the main part of said plate is recessed or made thinner than the ends; and a thin plate, l^2 , curved up on one edge, and having a curved knife, l , attached thereto, is secured to the plate L by set-screws passing through slots in the plate l^2 and into the plate L . Back of the folding-knife l and in the recessed plate L the counter for the embossing-tool is placed, and, if the counter is fitted so as to occupy all the space between the knife and the flange o^2 , it will retain its place properly. A recess is made in the bed of the machine, into which the plate L is placed so that the knife l will be directly beneath its counter f^1 in the embossing-plate. A feed-roller having longitudinal grooves therein, as shown at h , has its bearings in the frame B , and is caused to make intermittent rotary movements by the toothed wheel g and a ratchet within it, which wheel is operated by the toothed segment d' , to which is attached one end of the rod d'' , the other end being attached to the wheel K or to a crank-pin upon the shaft E' . The feeding-chain is made of a series of small plates, as shown in Figs. 8 and 9, which are jointed or hinged together at s' ; these joints being all upon one side of the chain, while the other side presents a general even or flat surface. To the upper or smooth side of the chain are attached the studs s'' , each having a slot extending entirely through it longitudinally with reference to the chain, and a tongue, t' , is inserted in this slot, said tongue extending through and having a pin, t^2 , placed in the tongue at the rear of the stud, so that after the tongue has been inserted and the pin secured in the tongue the latter cannot be withdrawn from the stud; and a piece of elastic is secured to the front end of the tongue at the lower part, the other end of the elastic being secured to the chain at t , or at any convenient distance from the tongue; and this elastic lies nearly flat upon the chain, and is of such length that when so secured the tongue is drawn out by the elastic until the small pin t^2 stops against the rear edge of the stud. These endless chains run upon the feed-rollers h and also upon the auxiliary feed-rollers h' at the other end of the table C , the joints or hinges s' dropping into the grooves in the feed-rollers h , said rollers, as they revolve, causing the chains to move intermittently along the surface of the table C . A recess, D' , is made along the table C , so that if a long collar is to be operated upon the outer chain e''' may be in the posi-

tion shown in Fig. 1; and if a shorter is to be made the chain e''' may be slipped along the feed-rolls h nearer to the middle of the table. To the uprights A upon the rear side of the plunger is secured a bar, H , to which are pivoted the two levers b , the long arm of each resting at the end upon the piece o , which is attached to the plunger G by the set-screw i , and the short arm of each resting upon a small rod, b' , which passes through a guide, i' , attached to the plunger G . To the lower ends of these rods b' is attached a bar, b'' , having the gauges b''' thereon. Behind the embossing and folding apparatus, and arranged upon the same frame B , is the punching apparatus having the table N between, and in order that the collars may pass through the whole machine easily the tables C and N and the top of the lower plate of the embossing and folding apparatus, together with the tops of the dies of the punching apparatus, are all upon nearly the same level or plane. The table N is similar in its construction to the table C having the feeding-chains e' moving along its surface, said chains moving the collar, after being embossed and folded, to the punches.

These punches are attached to the plunger P in the following manner: The plunger is operated in upright guide-ways by means of eccentrics upon the revolving shaft M , in a similar manner to the other plunger, G , and upon the top of the plunger P are made the ways v' , extending longitudinally along the plunger, and in these ways is a plate, v'' , fitted so as to slide freely therein, as shown in Figs. 11 and 12. The two end punches, having a screw-thread made upon the extreme upper end, pass up through this plate, and a nut, w' , is turned on at the upper end. Another plate, v^3 , is placed on the punch just below the plunger, with a nut beneath said plate, or a collar upon the punch-rod at this point, so that the plunger could bear upon it as it made its downward movement, would answer the purpose. A slot, y' , shown in Fig. 12, is made longitudinally in the plunger P , so that the punch-rod may be moved either way along the plunger, when necessary, and the nuts w^1 and w^2 may remain sufficiently loose, even while in use, that the plate v'' may find its own position directly over the punch-guide k^1 . The die-plates Q , for the two end punches, are made all in one piece with the guide k^1 , both being connected by the crook k^2 , and the die-plates, with their guides and punches, are all firmly secured to the bed S by set-screws q , passing up through the bed into the die-plates. The two end punches are each set with the crook k^3 , extending out toward the end of the bed-plate, so that the collars, as they are punched, may be carried through and pass off the end of the machine. The plunger has a transverse slot, z , made therein at the middle, and the middle punch has a screw-thread at the top, and is secured in any desired position by turning on the nut w^1 down firmly against the plunger, the punch having a shoulder thereon,

which is thus brought up against the plunger, holding the punch in its position. The die-plate for this middle punch is secured to the bed-plate by the set-screw in the same manner as the others are secured; but in adjusting the middle punch the punch itself and its die-plate have to be adjusted separately, either adjusting the punch first in the desired position, and then adjusting the die-plate to it, or vice versa. A cam, M'' , is placed upon the shaft M , and an upright lever, N'' , is attached to the inside of one of the uprights A^4 , the lower end of which lever is pivoted to a short horizontal lever, O' , one end of which is pivoted at O , and to the other end is attached an upright guide-rod, h'' , working in a guide, n , attached to each upright A^4 . There are two longitudinal levers, O' , and also two guide-rods, h'' , one of each attached to each upright A^4 , and a horizontal bar, m , is attached to the two guide-rods h'' , and to said bar m are secured vertical rods m' , the lower ends of which, when down, strike the top of the table. To cause the shafts E' and M to revolve, power is applied by the pulley F^3 , shaft E , and toothed wheels E'' and E''' .

The operation of my invention is as follows: The blank collars are laid upon the table C , and, as the chains e and e''' pass along beneath them, the collars are caught and moved along by the tongues t' coming against their edges; and as the plunger G rises the piece o upon the plunger raises the long arms of the levers b , which causes the short arms to force down the rods b' . This operation pushes down the gauges b''' , so that soon after the plunger begins to make its downward movement the gauges strike down upon the embossing-bed. The tongue t brings the collar up against the gauge, and if there be any irregularity in the placement of the studs s'' upon the chain; or if there are different collars of different widths being operated upon at different times, the elastic u stretches a little, the tongue pressing the collar against the gauges and springing back to accommodate the width of collar lying between the tongue and the gauge, the chain moving in the direction of the arrow in Fig. 9. This adjustment of the carrier, which moves the collar to the folding knife and embosser, as also to the punches, may be as well accomplished by means of a metallic spring placed either behind the movable carrier or in other convenient juxtaposition with the carrier, so that said movable carrier may attain the same nicety of movement in adjusting itself to the collars as they are carried up to the gauges. As the plunger continues its downward movement the rods b' are forced up again as the long arm of the levers b drop down, and when the plunger has completed its stroke, and has embossed and folded or creased the collar, as it commences its upward movement, the spring I presses against the rods b' , retaining them in their elevated position, and the collar is free to move on, and is carried along by the tongue

until it presses down over the feed-roller h . The movement of the collar has thus far been accomplished by the chains upon the folding and embossing-table; but the tongues v on the chains of the punching-table N , which are carried by the same feed-roller, take the collar as soon as the other chains leave it and carry it along to the punches. As the point of the cam M'' upon the punch-shaft M passes the upper crooked end of the upright rod N'' it is raised by the cam, and is quickly dropped again; and when the said rod is raised, the lever O' , bar m , and rods m' are all raised, leaving the collar free to be carried by the chain past the punches and off the end of the machine. When the rods m' are down in contact with the table N the collar to be punched is brought up against the said rods by the feeding-chains passing along the table N ; and when the cam M'' raises the lever and rods m' , then the collar is carried off the machine by the said chains after being punched. Whenever it is desirable to use knives having different curves for folding or creasing the collar, the plate b^2 may be detached from the bed by turning out the screws n^3 and attaching another of a different curve; and also taking out the counter f and substituting another corresponding with the curve of the knife to be used. When collars of different sizes are to be made different plates L are used, each plate for each size of collar being arranged with the recesses l' , of the proper distance from each other, in order that the feeding-chains will be guided so as to move against the collar, in carrying it to the embosser and folder, at each end. The guide C' is attached to the frame A^1 by screws C'' , in an inclined position with reference to the direction of the feeding-chains, and the auxiliary chain e''' is placed between the two main chains e , to carry one end of the collar until it nearly reaches the embosser, when the guide C' will have moved the collar over upon the chain e just outside the chain e''' , and the chain e''' , being carried upon an auxiliary roller placed beneath the table C , and in front of the embossing-bed, does not reach the embosser, the chains e carrying the collar beneath the embosser and upon the table N into a position to be carried by the chains e' to the punches.

Having thus described my invention, what I claim as new, and desire to secure by Letters Patent, is—

1. The feed-chain having the movable or elastic carriers t arranged thereon so as to give a proper adjustment to the collars as they are brought up to the gauges, substantially as described.

2. I claim the knife l attached to the plate b^2 , which is adjustable upon the bed by means of the set-screw n^3 , substantially as described.

3. I claim the knife-counter f , secured in place in the recess in the block G'' , substantially as and for the purpose described.

4. I claim the feed-chain e' , made movable

in a lateral direction, in combination with the feed-roller *h*, substantially as set forth.

5. I claim the feed-chains *e'*, arranged upon the table *N*, in combination with the feed-chains arranged upon the table *C* and the feed-roller *h*, as a means of moving the collars from the table *C* through the punches, substantially as described.

6. I claim the punch-guides *k'* and the die-plates *Q*, combined, and secured to the bed by a set-screw, *q'*, and having the punches se-

cured so as to be movable in the plunger *P*, substantially as set forth.

7. I claim the combination of the plunger *G*, the levers *b* pivoted to the bar *H*, spring *I*, rods *b'*, and gauges *b'''*, substantially as and for the purpose set forth.

CHAS. H. DENISON.
